E. BOGERT

WINDOW VENTILATOR

Filed Oct. 21, 1924

INVENTOR.

BY *Eugene Bogert*
Gifford Gause
ATTORNEY.

UNITED STATES PATENT OFFICE.

EUGENE BOGERT, OF RIDGEWOOD, NEW JERSEY, ASSIGNOR TO THE BOGERT & CARLOUGH COMPANY, OF PATERSON, NEW JERSEY, A CORPORATION OF NEW JERSEY.

WINDOW VENTILATOR.

Application filed October 21, 1924. Serial No. 744,884.

My invention particularly relates to a window ventilator which is adjustable and is readily and effectively retained in any desired position. Other objects of my invention will appear in the specification and will be particularly pointed out in the claims.

My invention will best be understood by reference to the accompanying drawings in which Figure 1 is a vertical sectional view taken along the plane of the line 1—1 of Fig. 2, and showing the window in dotted lines in a partially open position; Fig. 2 is a fragmentary front view of one side of the window ventilator; Fig. 3 is a horizontal section taken along the plane of the line 3—3 of Fig. 2 looking in the direction of the arrows; Fig. 4 is a vertical section taken through the upper portion of one of the side frames and through the sliding shoe which is mounted therein, and Fig. 5 is a sectional view taken along the plane of the line 5—5 of Fig. 2.

Like reference characters indicate like parts throughout the drawings.

Referring to the drawings, 10 indicates generally the upper portion of the window frame within which the swinging window ventilator is mounted, this portion of the frame in the form illustrated comprising a T-bar 11, the flange 12 of which is located on the outside of the wall and the rib 13 of which extends toward the inner portion of the wall. The upper portion of the frame 30 also comprises a bar 14 irregular in cross section, as indicated in Fig. 1, and provided with flanges 15 and 16, respectively, extending toward the window ventilator and forming seats for the upper portion of the sash of the window. The side frame (see Fig. 5) in the form shown, also comprises a T-bar 17 against which is secured a deep channel bar 18, the ends of which are engaged by the sash for the ventilator at the side of the window, as illustrated in Fig. 5.

In the form shown, the upper portion of the sash of the window ventilator is formed of a bar 20 Z-shaped in cross section, as illustrated in Fig. 1, while the sides and bottom of the sash are formed of T-shaped members 21—22, respectively, (see Figs. 5 and 1). The ventilator is preferably pivotally mounted at 23 on the upper ends of two swinging arms 24 at opposite sides of

the ventilator. Only one of the arms is illustrated at one side of the ventilator, it being understood that the opposite side of the ventilator is or may be formed the same as the side that is shown. The swinging arm 24, in the form shown, is pivoted at its lower end at 25 on a yoke-shaped bracket 26, the base of which may be secured to the side frame of the windows by bolts as at 27. In the closed position of the window ventilator the sash frame engages the window frame to form substantially tight joints, as indicated in Figs. 1 and 5. When the ventilator is moved to the open position, indicated in dotted lines in Fig. 1, the upper end of the arm 24 swings outwardly, the lower part 70 of the window swinging outwardly, while the upper portion thereof moves downwardly to the dotted line position indicated in Fig. 1.

In accordance with my invention, I provide means for readily and effectively retaining the ventilator in any position to which it may be desired to adjust the same. In the form shown guide members 28 on the side portions of the frame, and only one of which is shown in the drawings, are provided with a vertically extending slot preferably on the intermediate portion of the inside wall, as at 29 and as indicated in Fig. 3. The guide member is suitably secured 80 in the side frame in any desired manner. The guide member 28 is preferably formed of non-corrosive material such as bronze, brass or copper which is not substantially affected by atmospheric conditions. Within 85 the guide member 28 is mounted a sliding block or shoe 30, on one side of which is secured an outwardly bowed spring 31, the ends of which are received in suitable notches 32 formed in the shoe 30. The spring frictionally engages one side wall of the tubular guide 28 and forces the shoe into frictional engagement with the opposite wall of the tube. In the form shown, an arm 33 is bolted or otherwise secured to the top member 20 of the sash as by bolts 34, the outer end of the arm preferably being circular, as at 35, which is received in an opening 36 in the shoe or block 30. As the window is moved toward open position, the friction blocks or shoes 30 move downwardly in their guides, and the friction springs serve to retain the same in any position to

which they are moved and thus served to retain the window ventilator in any desired position.

Hitherto, with window ventilators of the general type here shown, it has been the common practice to paint the window frame, and the paint so applied has interfered with the movement of the ventilator. By forming the guide members of non-corrosive material such as bronze, brass or copper, it is unnecessary to paint the same. Furthermore, by forming the guide member in which the block or shoe is mounted tubular in form with only a slot at the inner side, which is closed by the side sash of the window when in closed position, it is impossible for the painter to reach the interior of the tube and apply paint thereto.

The friction shoe provided with a spring of the form shown is exceedingly simple both in construction and operation and does not require adjustment from time to time.

I claim:

1. In combination, a window frame, a metallic, unitary tubular guide, rectangular

in cross-section and having a narrow slot in its side, a shoe slidably mounted in said guide, a ventilating window swingingly mounted in the frame and provided with a pivot member extending through said slot and pivotally connected to said shoe and a spring member frictionally held on said shoe and engaging a side of the guide parallel to the axis of said pivot and arranged to press the shoe against the opposite side of the guide.

2. In combination, a window frame, a metallic, unitary tubular guide, rectangular in cross-section and formed of non-corrosive metal and having a narrow slot in its side, a shoe slidably mounted in said guide, a ventilating window swingingly mounted in the frame and provided with a pivot member extending through said slot and pivotally connected to said shoe and a spring member frictionally held on said shoe and engaging a side of the guide parallel to the axis of said pivot and arranged to press the shoe against the opposite side of the guide.

EUGENE BOGERT.
